John J. Lee.
INVENTOR

BY *Victor J. Evans*
ATTORNEY

UNITED STATES PATENT OFFICE.

JOHN J. LEE, OF CHICAGO, ILLINOIS.

CARD HOLDER.

Application filed May 13, 1921. Serial No. 469,248.

To all whom it may concern:

Be it known that I, JOHN J. LEE, a citizen of the United States, residing at Chicago, in the county of Cook and State of Illinois, have invented new and useful Improvements in Card Holders, of which the following is a specification.

This invention relates to card holders and an object of the invention is to provide 10 a device which is simple in construction and may be easily and quickly attached to any suitable object such as a cigar box, cartons or boxes used for containing candies or various other mercantile articles, whereby 15 a price card or a card setting forth the merits of the article may be supported from the container.

Another object of this invention is to provide 20 a card holder as specified which is constructed of spring wire bent to provide spaced attaching and card gripping portions, each of which include looped portions having their terminals sharpened for biting 25 into the container or card, which biting action is urged or augmented by the resiliency imparted to the loops by their formation.

Other objects of the invention will appear 30 in the following detailed description and in the accompanying drawing wherein:

Fig. 1 is a front elevation of the improved 35 card holder showing it applied.

Fig. 2 is an edge elevation of the improved 40 card holder showing it applied.

Fig. 3 is a front elevation of the improved 45 card holder.

Fig. 4 is a section on the line 4--4 of Fig. 5.

Referring more particularly to the drawing 40 the improved card holder comprises an attaching portion 1 and a card carrying portion 2 which are connected by the connecting portion 3. The improved card holder is formed preferably of two lengths of resili- 45 ent wires which are twisted together to provide the connecting portions 3 and a unitary structure. The upper end portions 4 and 5 of the lengths of wire are bent laterally and shaped to provide downward- 50 ly extending card gripping loops 6 each of which comprises the back portion 7 adapted to engage the back of a card as shown at A and the upturned forward portion 8, the terminal of which is bent inward-

ly and downwardly to provide the card 55 engaging end 9. The ends of the card engaging ends 9 are preferably sharpened so that they will bite into the card A and securely hold it in place in the holder. The formation of the loops 6 and the resiliency 60 of the wire urge the ends 9 into card gripping positions.

The lower end portions 10 and 11 of the 65 lengths of wire are also bent laterally and have package gripping portions 12 formed on their terminals which package gripping portions are similar in construction to the card gripping portions 8 being reversed, however, as clearly shown in Fig. 2 of the drawing and the upturned sharpened terminals 13 are urged into package gripping position by the resiliency of the wire and the bendings at 14 of the loop structures 12. The terminals 9 and 13 biting into the card A and package B respectively will prevent 75 the accidental disconnection of the holder from the package or the card from the holder and the card will be maintained in upright exhibiting position.

It will be apparent, from the foregoing 80 description taken in connection with the accompanying drawing that the improved card holder may be manufactured at a relatively low cost and that it may be easily applied to a package and will not tilt or become 85 loose on the package during use. To remove the card holder it is only necessary to spring the loop portions 6 and 12 to move the ends 9 and 13 out of biting or gripping position.

It is, of course, to be understood that the 90 invention may be constructed in various other manners and the parts associated in different relations and, therefore, I do not desire to be limited in any manner except as set forth in the claim hereunto appended. 95

Having thus described my invention what I claim is:

In a card holder, a pair of lengths of wire twisted together intermediate their ends and having their end portions bent 100 laterally in two directions, said laterally bent portions being shaped to provide a pair of spaced gripping loops at each end of said twisted portion, the terminals of said loops being inturned and urged into article 105 gripping position by said loops.

In testimony whereof I affix my signature.
JOHN J. LEE.
